UNITED STATES PATENT OFFICE.

WILMER S. SNOW, OF CHICAGO, ILLINOIS.

DESIGN FOR A LIGHTING-FIXTURE.

49,627.

Specification for Design.

Patented Sept. 5, 1916.

Application filed July 22, 1916. Serial No. 110,807. Term of patent 7 years.

To all whom it may concern:

Be it known that I, WILMER S. SNOW, a citizen of the United States, residing at Chicago, in the county of Cook and State of Illinois, have invented a new, original, and ornamental Design for a Lighting-Fixture, as shown, reference being had to the accompanying drawings, forming a part thereof.

In the drawings, the figure is an elevation of my lighting fixture.

I claim,—

The ornamental design for a lighting fixture, as shown.

Signed at Chicago, in the county of Cook, and State of Illinois, this 15th day of July, 1916.

WILMER S. SNOW.
